UNITED STATES PATENT OFFICE.

CHARLES W. LORD, OF PAWTUCKET, RHODE ISLAND.

BRACELET.

SPECIFICATION forming part of Letters Patent No. 357,326, dated February 8, 1887.

Application filed September 9, 1885. Serial No. 176,643. (No model.)

To all whom it may concern:

Be it known that I, CHARLES W. LORD, of Pawtucket, in the county of Providence and State of Rhode Island, have invented a new 5 and useful Improvement in Bracelets and Similar Articles; and I do hereby declare the following specification, taken in connection with the accompanying drawings, forming a part of the same, to be a description thereof.

10 The invention consists in a bracelet or similar article, the back member of which has its edges turned over or bent to form hook portions, and the front member of which has its edges turned over or bent to form hook portions, the two members being held in a fixed 15 relation to each other by the engagement of their hook portions, whereby a bracelet of any desired thickness can be made and the front member be held in a desired relation to the face 20 of the bracelet without the interposition of a filling between the back and front members, as hereinafter described and claimed.

In the accompanying drawings, Figure 1 shows a side view and partial section of a bracelet 25 embodying the invention. Fig. 2 shows an end view of the same. Fig. 3 represents, on a larger scale, a transverse section of the same, the edges of the back member being bent into circular form. Fig. 4 shows a transverse section 30 of a bracelet embodying the invention, with the edges of the back member bent into rectangular form. Fig. 5 represents a transverse section of a bracelet, with the edges of the back member bent into triangular form.

35 A is the back member, which is bent or arranged to form the lining a , the sides a' , and portions a'' of the face of the bracelet. The edges of the back member are turned over or bent to form hook portions a^3 a^3 , for engaging 40 the front member and holding it suspended in place.

B is the front member, which has its edges turned over or bent to form hook portions b b , which engage the hook portions a^3 a^3 of the 45 back member and hold the two members in the desired relation to each other.

In the manufacture of the bracelet the back and front members are preferably separately

formed into proper shape, and then combined by sliding the member B endwise into the member A, the hook portions a^3 a^3 b b engaging each other, and thereby hooking or suspending the front member in a fixed relation to the back or lining a and the face portions a'' of the member A, as shown in all the figures of the 55 drawings.

By hooking the front member to the back member, as above described, a "box" bracelet of any thickness may be made and the front member be held in the desired relation 60 to the lining a and face portions a'' of the back member, without the interposition of any filling material between the two members to hold the front member in the desired place, as will be readily understood.

I am aware that thin or "band" bracelets have been made having the edges of the back member turned over parallel with the body portion thereof, so as to furnish grooves into which a flat-face member, or one with unturned 70 edges, can be slid, and I do not claim such a construction, the two members not being hooked to each other, or, in other words, the front member not being suspended by and upon the back member by the engagement of hooked 75 portions on the edges of each member.

What I claim, and desire to secure by Letters Patent, is—

1. As a new article of manufacture, a bracelet having its front and back plates forming the 80 band united together by continuous hooked opposite edges on one interlocked with continuous hooked opposite edges on the other, substantially as shown and described.

2. A bracelet comprising a band made of a 85 front plate having its opposite edges formed with hooks and a back plate having its opposite edges formed with similar hooks, the hooked edges of the front plate being interlocked with the hooked edges of the back 90 plate, substantially as described.

CHARLES W. LORD.
